UNITED STATES PATENT OFFICE.

ORLA H. IMAN, OF CHICAGO, ILLINOIS, ASSIGNOR, BY MESNE ASSIGNMENTS, TO
WATSON SOLAR WINDOW COMPANY, OF CARMEL, NEW YORK, A CORPORATION
OF NEW YORK.

METAL-FRAME WINDOW.

1,086,533.

Specification of Letters Patent.

Patented Feb. 10, 1914.

Application filed May 11, 1911. Serial No. 626,400.

To all whom it may concern:

Be it known that I, ORLA H. IMAN, a citizen of the United States, residing at Chicago, in the county of Cook and State of Illinois, have invented certain new and useful Improvements in Metal-Frame Windows, of which the following is a specification.

This invention relates to improvements in metal frame windows, and has reference more particularly to improvements in that type of window which has come to be known to the trade as the "fenestra type".

A leading object of the invention is to provide a construction adapted for the use, interchangeably, of a fixed panel or a pivoted panel without necessitating any change in the window structure itself in order to effect the substitution of one for the other. It sometimes happens that where windows of this type employing fixed or non-opening sash or panels, have been installed in factories, complaint is made that they do not afford opportunity for ventilation through the window opening, and hence it is desirable to render such windows capable of easy modification in such a way as to provide for the employment of an operable sash or panel therein, and this my present invention accomplishes.

Another object of the invention is to provide a new and useful structure of pivoted sash which may be readily substituted for one or more of the glass panels in such a window without involving any alteration in the structure of the latter.

Still another object of the invention is to equip such an openable sash with a suitable weather-stripping provision that shall give to the movable sash when in closed position, substantially the character and effect of a permanent sash or panel, so far as protection against the outside elements is concerned.

Other minor objects and advantages of the invention will be apparent from the following description, taken in connection with the accompanying drawings, in which—

Figure 1 is an inside elevation of a window, broken off at its lower end, constructed in accordance with my invention. Fig. 2 is an enlarged cross-sectional detail on the line 2—2 of Fig. 1. Fig. 3 is an enlarged vertical section, broken out between its ends, on the line 3—3 of Fig. 1. Fig. 4 is an en-

larged inner side elevation of the pivoted sash and its mounting, broken off at one side and between its ends. Fig. 5 is an enlarged detail in perspective, showing the manner of pivoting the sash to the parts by which it is removably mounted in the frame. Fig. 6 is a perspective elevation of the upper combined attaching device and weather-strip. Fig. 7 is a similar perspective of one of the stiles of the sash. Fig. 8 is a similar view on the lower combined attaching device and weather-strip. Fig. 9 is a perspective elevation of a connecting strip that unites the two members shown in Figs. 6 and 8.

Referring to the drawings, 10 designates the vertical members and 11 the upper horizontal member of a rectangular jamb-frame adapted to be permanently set in the wall of a building. These are hollow sheet-metal structures provided on their inner sides with grooves or channels, such as 11^a adapted to seat the upper marginal portions of the glazing. The structure herein shown also includes a hollow sheet-metal central cross-bar 12 likewise formed in its upper and lower edges with grooves or channels 12^a to receive the marginal portions of the glazing lying directly above and below said cross-bar, this latter dividing the entire window structure into a pair of upper and lower duplicate sections. The sections thus formed are each subdivided by muntins into a plurality of glass panels, and may, of course, be further subdivided if desired, by one or more transoms into a greater number of smaller panels; the number of muntins and transoms employed being optional and immaterial to the structural features involved in the present invention.

For the sake of simplicity of illustration, I have herein shown each of the upper and lower window sections as divided by a pair of muntins 13 into three panels, the stationary glazing of each of which is designated by 14. The muntins 13 are of hollow sheet metal construction, and each is a two-part structure comprising an outer permanent section 13^a (Fig. 2) and a similar inner removable section 13^b. These sections preferably have substantially the cross-sectional form illustrated in Fig. 2, and the outer sections 13^a are permanently secured at their upper and lower ends in the end and intermediate cross-bars of the jamb-frame, while the inner sections 13^b are removably secured

at their ends in said cross-bars, for which purpose the latter are provided with openings of the cross-sectional form and dimensions of the muntin-bar 13^b, through which openings the ends of the latter may be readily inserted and withdrawn, the lower ends of said removable muntin bars 13^b, when in operative position, being stepped upon suitable supports indicated at 15 in

10 Figs. 3 and 4.

Where the muntins between the cross-bars in which they are secured at their ends are of considerable length, it is desirable to provide intermediate connecting devices be-

15 tween the outer and inner bars of each pair, for which purpose I have shown a connecting link 16 (Fig. 2), which is pivoted at 17 between the side walls of the outer muntin bar 13^a, and at its free end, extends across

20 between the inner sides of the side walls 13^b, being provided at its free end with a hole adapted to receive a bolt 18 passed through the side walls of the muntin bar and the hole in the connecting link and secured by a nut.

25 19. The links 16 are located at any desired point or points along the length of the muntin bars and serve to tie the latter together between their ends; and when it is desired to remove the inner muntin bar 13^b, the bolt

30 18 is withdrawn, the link 16 swung to a position in which it lies vertically wholly within the outer muntin bar 13^a, the muntin bar 13^b is then raised sufficiently to clear its inner end from the lower cross-bar, where-

35 upon its upper end may then be withdrawn from the aperture in the upper bar. The simple converse of these operations is performed in inserting the removable muntin bar to operative position in the window.

40 40. The structure as thus far described is substantially identical with that disclosed and claimed in a copending application filed May 11, 1911, in the names of William D. Watson and Orla H. Iman, Serial No. 626,410, and no claim to this construction, *per se*, is made by me herein; although certain features of this construction are well adapted for coöperation and combination with those features in which my present in- 50 vention more particularly resides, and which will next be described.

45 20 designates a glass panel that is mounted in a sash frame, which latter is adapted to be pivotally mounted in any one of the 55 panels of the window, formed between adjacent muntins in lieu of a stationary or fixed panel such as those shown at 14. The frame of this pivotal sash comprises, as herein shown, a pair of stiles 21 (Fig. 7) of 60 hollow sheet metal and approximately round in cross-section, each of said stiles being formed with integral glass-holding lips 22 on its inner side. The stiles 21 are connected at their upper and lower ends to cross-bars 65 23, which latter are of the same form as the

stile 21, forming miter joints with the latter, and preferably connected by internal L-shaped connectors 24. Coöoperating with the sash thus formed is a sash holding frame that is preferably so formed as to have also 70 the character of a weather-strip frame, and is made in two (upper and lower) sections: the upper section engaging the outer side of the upper half of the sash and the lower section 75 engaging the inner side of the lower half of the sash when the latter is in closed position. Each of these sections is, as herein shown, made up of a plurality of connected weather-strips, and the two main sections are connected together at their inner 80 or meeting ends, and the entire sash-holding frame thus formed is provided with outer marginal tongues that are adapted to have the same engagement with the grooves of the cross-bars of the main frame and with the muntins as the marginal portion of a plain glass panel. A pair of these weather-strips which coöperate with the right-hand stile of the sash are clearly shown in the perspective views, Figs. 6 and 8, in which 25 is 85 the lower strip formed with the bent longitudinal tongue 25^a on its outer edge, and 26 is the upper strip formed with a similar bent longitudinal tongue 26^a on its outer edge. Similar transversely extending strips 90 27 and 28 are secured to the upper and lower ends of the strips 26 and 25, respectively, by internal L-shaped connectors lying within the tongued extensions thereof, as clearly shown at 29 in Figs. 3 and 4.

95 To the stiles 21 are secured by screws or rivets 30 the upper members 31 of hinges, the lower members of which, indicated by 32, are secured by screws or rivets 33 to the upper end of the lower section of the sash holding frame, the hinge pivot being shown at 34. The lower and upper strips 25 and 26 on each side are, in turn, connected at their meeting ends by straight bar connectors 35 that lie within and are secured to the tongue extensions 25^a and 26^a of said members. Fig. 9 shows a detail of the connector bar 35 which extends for about half its length into the upper end of the tongue 25^a of the strip 25 and for the remaining 115 half its length into the lower end of the tongue 26^a of the strip 26, being secured to said parts by screws or rivets indicated at 36 in Fig. 4. From this it will be seen that the entire sash-holding frame is permanently connected to the pivoted sash through the pivot of the latter, and that the sash-holding frame comprising the vertical sections 25 and 26 on both sides, the transverse sections 27 and 28 at the upper and lower ends, and the connecting pieces, has a continuous outer marginal tongue that is of substantially the same thickness as the glazing in the panels 14. Hence, assuming 120 that the window as originally installed has 125 130

only fixed glass panels, and the owner or tenant of the building desires more ventilation, this is easily and readily secured by simply taking off the removable muntin bars 13^b, taking out the glass panel (which is done by raising the latter through a slot 11^b, Fig. 3, formed in the upper channel 11^a sufficiently to clear its lower edge and then withdrawing its upper edge), inserting in place thereof the pivoted glazed sash with the sash-holding attachment, and then again applying the removable muntin bars which engage and clamp the marginal tongues of the sash-holding frame in the same manner that the margins of the glass were formerly engaged and clamped. By the same operation, a pivoted sash such as I have described originally installed in a window can be withdrawn and a fixed glass panel substituted therefor, if desired. This capacity of the structure which provides for the ready interchangeability of a fixed and pivoted panel constitutes a very important feature of my present invention, since it not only makes unnecessary the substitution of an entire new window when a change is desired to secure or dispense with ventilation, but it enables such a change to be effected by a very simple and easily effected modification of the original structure. Furthermore, it will be seen that the sash-holding frame in the preferred form herein shown performs weather-strip functions for the pivoted sash when the latter is closed, as well as constituting the direct or immediate supporting frame therefor, to which the sash is directly pivoted, and also carrying the parts which engage the grooves or channels of the muntins and cross-bars of the window frame.

It will be manifest to those skilled in the art that the exact forms and relative arrangements of the structural parts herein shown are not of the essence of the invention, but may be modified to a considerable extent without involving any departure from the principle involved or sacrificing any of the benefits and advantages attained thereby.

50 I claim—

1. In a metal frame window, the combination of a hollow sheet metal sash formed on its inner edges with glass-holding grooves, a containing metal frame formed on its inner edges with grooves of the same width as the grooves of said sash, and a sash-holding frame on and within which said sash is pivotally mounted, said sash-holding

frame having on its outer edges marginal tongues adapted to be held in the grooves 60 of said containing frame, substantially as described.

2. In a metal frame window, the combination with a containing frame grooved on its inner edge, of a sash, and a weather-strip frame formed in upper and lower sections engaging the outer and inner sides, respectively, of said sash, said sash being hinged to the upper end of said lower weather-strip frame section and said weather-strip frame sections being formed with hollow marginal tongues adapted to be held in the grooves of said containing frame, and connectors for said weather-strip frame sections fitted within and secured to the 75 meeting end portions of the hollow marginal tongues of the latter, substantially as described.

3. In a metal frame window, the combination with a main frame having cross-bars 80 grooved on their inner sides, the bottom of the groove of the upper cross-bar being slotted, and a pair of muntins, each comprising a fixed muntin bar and a removable muntin bar, of a sash, and a sash-holding frame in 85 which said sash is pivotally mounted, said sash-holding frame being provided with marginal tongues adapted to enter the grooves of said cross bars of the main frame and to be confined between the fixed and removable muntin bars of said muntins, substantially as described.

4. In a metal frame window, the combination with a main frame having cross bars grooved on their inner sides, the bottom of the groove of the upper cross bar being slotted, and a pair of muntins, each comprising a fixed muntin bar and a removable muntin bar, of a sash, and a weather-strip frame formed in upper and lower sections 100 engaging the outer and inner sides, respectively, of said sash, said sash being pivotally mounted on the upper end of said lower weather-strip frame section, and said weather-strip frame sections being connected 105 at their meeting ends and formed with marginal tongues adapted to enter the grooves of said cross bars of the main frame and to be confined between the fixed and removable muntin bars of said muntins, substantially as described.

ORLA H. IMAN.
